10 Claims. (Cl. 33—62)

In all sun dials at present known use is made of the shadow of a style on a table, which is a flat or curved surface on which the hour lines are traced.

In sun dials having vertical, oblique or horizontal tables, the setting of the style and the tracing of the hour lines must be determined in different manners depending on the place in which the apparatus is used.

Equatorial sun dials and cylindrical sun dials are free from these difficulties of construction, but the former, in which the tables are flat and parallel to the plane of the equator are inaccurate at times of the equinoxes, while the latter, which use as tables complete cylinders of revolution one of the ends of which is open, permit only very difficult reading of the shadows.

The present invention, which relates to a new sun dial free from the above-mentioned disadvantages, consists of a curved, open, suitably selected surface on which the hour lines are traced.

The curved surface is geometrically defined as a "concave ruled surface" which means that the surface is produced by a straight line generatrix moved in a position parallel with a stationary straight line along a curve which has no breaks and contains no change in the direction of its curvature. Thus, this term also includes cylindrical surfaces in which case, as is well known, the cross-section need not be a circular arc. Therefore, in the following specification and in the claims the term "concave cylindrical surface" is intended to define broadly a "concave ruled surface" as stated above.

Two parallel generatrices which bound the said concave cylindrical surface act as style.

The invention permits the serial production of inexpensive apparatuses which everywhere show the legal time to within one minute.

Many different surfaces may be used. There are numerous mechanical constructions permitting their positioning in accordance with the place where they are used.

The present invention likewise relates to other arrangements which will be explained below in the description of the dials illustrated in the accompanying drawings, in which:

FIGURE 1 is a view in elevation of a first sun dial according to the present invention and of the various means of support and regulation of the said dial,

FIGURE 2 is a view of a detail of the said dial,

FIGURE 3 is a partial view of the sun dial illustrated in FIGURE 1, viewed in the direction of the arrow f,

FIGURE 4 is a section along the line IV—IV in FIGURE 3, and

FIGURE 5 is a view of a second sun dial according to the present invention and of the various means of support and regulation of the said dial.

The sun dial illustrated in FIGURES 1 to 4 is here constituted by a partial cylinder of revolution 1. The generatrices 1a and 1b, which coincide with the edges of said partial cylinder 1 and are spaced from each other a distance subtending an angle or arc $\alpha = 150^\circ$ of said cylinder.

When the generatrices 1a and 1b and the axis 1c of the said cylinder are on the one hand parallel to the meridian plane of the place where the sun dial is installed, passing through the axis of the said cylinder, and when these generatrices are parallel to the axis of the

2

poles of the earth, the shadows cast by the generatrices 1a or 1b on the dial formed by the cylinder 1 give the true local time. The cylinder 1 bears a number of hour line 1d, each of these lines corresponding to two times, 5 differing from one another by five hours, depending on whether the shadow is cast by the generatrix 1a or the generatrix 1b.

The cylinder 1 is solid with a stirrup 2 adapted to pivot around an imaginary line formed by the axes of two buttons 4 and 5 carried by a stirrup 3. This line is parallel to the generatrices of the cylinder 1.

The stirrup 3 forms one side of a deformable triangle constituted by a bar 8 and a cursor 9 adapted to move in a U-shaped channel member 10. Hinges 6, 7, and 11 connect the parts 3, 8, 9, and 10 together. The said channel member 10 carries a latitude graduation scale.

The channel member 10 rests on a disc 12 which is fixed by screws 13 to a base 14, having three feet formed by adjusting screws 15.

20 A screw 17 passing through the disc 12 serves as axis of rotation for the channel member 10 and passes through a longitudinal slot provided in the cursor 9. A button 16 cooperating with the screw 17 enables the channel member 10 to be clamped angularly relative to plate 12 and the cursor 9 to be clamped longitudinally relative to screw 17.

25 On the stirrup 3 is fixed a plate 18, which carries a longitude graduation scale 18b and a bean-shaped time curve 18a.

A pointer 19 pivoting around the axis of the button 4 is adapted to move in front of the plate 18, so that when the button 4 is tightened the pointer 19 forms a rigid whole with the stirrup 2 and the cylinder 1.

Finally, the two stirrups 2 and 3 can be clamped together by a pin 20 or by the button 5.

For the purpose of installing this sun dial the procedure is advantageously as follows:

In order to set the channel 10 horizontally, the positions of the screws 15 are adjusted in a manner known per se by means of a water level.

40 In order to adjust the apparatus to latitude, the button 16 is loosened, the cursor 9 is so adjusted as to have its end on the latitude scale graduation provided on the bottom of the channel member 10, which corresponds to the latitude of the place where the sun dial is installed, 45 and the button 16 is tightened again.

In order to adjust the apparatus, the axis 1c of cylinder 1 must be brought parallel to the earth's axis. For this purpose it is now sufficient to bring the channel member 10 into the local meridian plane. The cylinder 1 is 50 clamped to the assembly 3, 9, 10, 8, by means of the pin 20. The button 4 is loosened and consequently the pointer 19 released and the latter is set to the graduation of the longitude scale 18b corresponding to the longitude of the apparatus in relation to the Greenwich meridian. 55 The pointer 19 is finally clamped again by tightening the screw button 4 to the stirrup 2 and the cylinder 1.

The pin 20 is removed and the button 5 loosened. The assembly 1, 2, 19, can then be turned in relation to the assembly 3, 18. The assembly 1, 2, 19 is turned 60 so that the pointer 19 is set to the graduation of the time curve 18a corresponding to the date on which the instrument is installed. The assembly 1, 2, 19 is again clamped to the assembly 3, 18, by tightening the button 5.

65 The direction of the apparatus is then adjusted by loosening the button 16 and the entire apparatus is adjusted so that the shadow of the generatrix 1a or 1b on the cylinder 1 indicates the legal time, and the button 16 is finally tightened again. The apparatus is then 70 in position.

Every ten days the apparatus must be re-adjusted. For this purpose the button 5 is released and the pointer

19 is set to the graduation of the time curve 18a corresponding to the date of the correction and then the button 5 is tightened again.

The apparatus thus shows the legal time throughout the year to within 1 minute.

Diurnal shadow lines or lines of equal dates can easily be traced on the dial of this instrument. The latter then becomes self-regulating because it can be installed without the time being known.

In the apparatus illustrated in FIGURE 5, the stirrup 2 is mounted directly on the raised end 9b of the cursor 9. The button 5 and also the plate 18 and its pointer 19 are eliminated. The pin 20 is then placed on one of the sides 2a of the stirrup 2 and on a part 21, solid with a part 22 articulated by means of the hinge 6 on the bar 8. 10 15

The remainder of the apparatus is similar to that illustrated in FIGURES 1 and 2.

In order to install this last-mentioned sun dial, the procedure may be as follows:

In order to set the channel member 10 horizontally and to regulate the apparatus for latitude, the procedure is as before.

In order to orient the apparatus, that is to say in order to bring the channel member 10 into the meridian plane passing through the place where the sun dial is situated, the procedure is as follows: the pin 20 remains engaged, the button 16 is loosened, and the instrument is brought into a position such that the difference between the time indicated on the cylinder 1 by the shadow cast by the generatrices 1a and 1b and the legal time is equal to a value given by a table in dependence on the date on which the instrument is being installed and on the longitude of the place in relation to the Greenwich meridian. The button 16 is then tightened. The channel member 10 is then in the meridian plane of the place. 30

In order to adjust the position of the cylinder, the pin 20 is removed and the cylinder 1 turned until the aforesaid difference is equal to zero, and the assembly is clamped by means of the button 4.

The apparatus is then adjusted in place.

Every eight days the button 4 is loosened and the cylinder 1 and its stirrup 2 turned until it indicates the legal time, and the button 4 is tightened again.

It should be observed that the accuracy of the instruments described is twice as great as that of cylindrical dial instruments having axial styles, because in the instruments according to the present invention the generatrices 1a and 1b are in the dial surface, whereas in the cylindrical instruments having an axial style the style is in the centre. 50

The present invention is not limited to the examples described. Thus, for example, the dial is not necessarily constituted by a split cylinder of revolution. This dial may in fact be constituted by a skew surface bounded by two parallel generatrices. In particular, where use is made of a hyperboloid of one sheet, the dial carries crossing hour lines.

I claim:

1. A sundial apparatus, comprising, in combination, opaque dial plate means having a concave cylindrical indicating surface adapted to be exposed to incident sunlight and to unobstructed view, and defined geometrically as a portion of a cylindrical surface extending between two parallel edges each coinciding with a generatrix of said indicating surface and being located in generally opposed direction across said indicating surface, said indicating surface being provided with a plurality of index lines respectively associated with different hours of the day; and means for orienting said dial plate means at least depending upon latitude and longitude of the location of the apparatus, so that the time indication is effected on said indicating surface of the dial plate means in relation to said index lines by the edge of the shadow 70

of a portion of said opaque dial plate means, said edge of the shadow being a projection by sunlight of one of said edges of said dial plate means.

2. A sundial apparatus, comprising, in combination, opaque dial plate means having a concave indicating surface adapted to be exposed to incident sunlight and to unobstructed view, and defined geometrically as a portion of a cylindrical surface extending between two parallel edges each coinciding with a generatrix of said cylindrical surface and being spaced from the other generatrix a predetermined distance substantially diametrically across said cylindrical surface, said indicating surface being provided with a plurality of index lines respectively associated with different hours of the day; and means for orienting said dial plate means at least depending upon latitude and longitude of the location of the apparatus, so that the time indication is effected on said indicating surface of the dial plate means in relation to said index lines by the edge of the shadow of a portion of said opaque dial plate means, said edge of the shadow being a projection by sunlight of one of said edges of said dial plate means. 20

3. A sundial apparatus, comprising, in combination, opaque dial plate means having a concave indicating surface adapted to be exposed to incident sunlight and to unobstructed view, and defined geometrically as a portion of a cylindrical surface extending between two parallel edges each coinciding with a generatrix of said cylindrical surface and being spaced from the other generatrix a predetermined distance subtending a 150° arc of said cylindrical surface, said indicating surface being provided with a plurality of index lines respectively associated with different hours of the day; and means for orienting said dial plate means at least depending upon latitude and longitude of the location of the apparatus, so that the time indication is effected on said indicating surface of the dial plate means in relation to said index lines by the edge of the shadow of a portion of said opaque dial plate means, said edge of the shadow being a projection by sunlight of one of said edges of said dial plate means. 30 35

4. A sundial apparatus as claimed in claim 1, wherein said opaque dial plate means include support means turnable about an axis parallel with the geometrical axis of said cylindrical surface, and wherein said means for orienting said dial plate means include pivot means turnably supporting said dial plate support means for turning movement about said axis and clamping means for setting said dial plate means in a desired oriented position. 40

5. A sundial apparatus as claimed in claim 3, wherein said opaque dial plate means include support means turnable about an axis parallel with the geometrical axis of said ruled surface, and wherein said means for orienting said dial plate means include pivot means turnably supporting said dial plate support means for turning movement about said axis. 50

6. A sundial apparatus as claimed in claim 4, wherein said means for orienting said dial plate means include a triangular supporting frame composed of a plurality of frame members, one frame member carrying said pivot means and being adjustable to a desired inclination relative to a second one of said frame members. 60

7. A sundial apparatus as claimed in claim 5, wherein said means for orienting said dial plate means include a triangular supporting frame composed of a plurality of frame members, one frame member carrying said pivot means and being adjustable to a desired inclination relative to a second one of said frame members. 65

8. A sundial apparatus as claimed in claim 6, wherein said triangular frame comprises a plurality of hingedly connected frame members, one of said frame members being composed of at least two portions, one of which is longitudinally adjustable relative to the other portion for varying the length of that particular frame member, said other portion carrying a latitude scale and said adjustable portion being movable relative to said scale so

that it can be set to a position relative to said scale which determines a desired inclination of said axis of said dial plate means.

9. A sundial apparatus as claimed in claim 8, wherein said one frame member carrying said pivot means includes a plate member carrying a longitude scale, and wherein said dial plate support means include an index member movable relative to said longitude scale for indicating the setting of said dial plate means corresponding to a particular longitude when said dial plate means are correspondingly turned about its axis.

10. A sundial apparatus as claimed in claim 9, including an indexed time correction curve arranged on said

plate member for cooperation with said index member and permitting adjustment of said dial plate means in consideration of the difference between apparent time and clock time.
